VENDING MACHINE ROTARY ARTICLE CARRIER HAVING CAPACITY INCREASING DIVIDER STRUCTURE

Elmer C. Johnson, Raytew, Mo., assignor to The Vendo Company, Kansas City, Mo., a corporation of Missouri

Filed May 20, 1963, Ser. No. 281,633
11 Claims. (Cl. 312—97.1)

This invention relates to vending machines, and more particularly to apparatus for increasing the capacity of machines having rotatable product-supporting shelf structure.

It is well known to construct vending machines having rotatable shelves which are divided into a series of compartments, each of which may be rotated into registry with a product delivery opening in the machine. A complete description of such a machine has been set forth in my copending application entitled "Universal Vending Apparatus," Serial No. 42,408, filed July 12, 1960, now Patent No. 3,122,401, granted February 25, 1964, and which is incorporated into this application by reference.

Although vending machines of this type have met with widespread commercial success, one major disadvantage has presented itself when the machines are used for vending certain products. By virtue of the utilization in such machines of rotatable shelf structure of generally circular construction, the dividing of the shelves by radially extending partitions results in generally wedge-shaped compartments. Although this shape is well suited for certain products, many of the products to be vended have relatively circular or rectangular perimeters. The wedge shape of the compartment requires that the radial dimension thereof be rather large compared to the dimension of the product and this has, in the past, resulted in the waste of much of the space in the vending machine. This space loss has, in turn, dictated more frequent operator attention to the machines and also has resulted in loss of sales when the compartments were permitted to become empty.

It is, therefore, the primary object of the instant invention to increase the capacity of a rotatable shelf vending machine by providing novel structure to present, in heretofore wasted space, compartments from which additional products may be vended.

It is another important object of this invention to provide such capacity increasing structure which may be economically fabricated and quickly and easily installed in the vending machine so that the cost of providing the structure does not outweigh the economical advantages attendant with the increased vending capacity available with machines equipped with such structure.

Still a further object of the invention is to provide structure wherein the additional product compartments are positively locked to prevent pilfering until the machine has been properly operated by deposit therein of the proper amount of money by the customer.

Another object of the invention is to provide space-increasing structure including additional product compartments spaced to the rear of forward compartments and which are accessible to the customer through the forward compartments while the latter are still aligned with the delivery opening.

A yet further object of the instant invention is to provide shelf structure having novel product dividing partitions wherein the forward compartments remain in registry with the delivery opening through a greater arc of rotation of the shelf than is necessary to allow removing of the product therefrom, thus permitting the shelf to be rotated for unlocking the rear compartment with-

2

out moving the forward compartment from registry with the opening.

These and other important objects, advantages and details of construction of the present invention will become obvious or be explained in greater detail as the following specifications progresses.

In the drawings:

FIGURE 1 is a fragmentary, horizontal, cross-sectional view through a vending machine embodying the concepts of the instant invention, parts being broken away and shown in cross section to reveal details of construction;

FIG. 2 is a fragmentary view taken along line 2—2 of FIG. 1;

FIG. 3 is a fragmentary view taken along line 3—3 of FIG. 1, parts being broken away to reveal details of construction;

FIG. 4 is a fragmentary, horizontal, cross-sectional view similar to FIG. 1 but showing the pivotal door in the product vending location thereof;

FIG. 5 is a fragmentary, vertical, cross-sectional view through the machine showing one shelf assembly of the machine embodying the concepts of this invention, parts being broken away for clearness; and

FIG. 6 is a fragmentary, front elevational view of the shelf flange showing the slots therein with clips positioned in the preferred sequence for proper operation of a vending machine incorporating the novel structure of this invention.

The structure embodying the principles of the instant invention includes a rotary article-carrying assembly broadly designated 10 which is adapted to be utilized in a vending machine 12 having insulated side walls 14 defining a product delivery opening 16.

A vending machine utilizing the principles of this invention will normally be provided with a plurality of assemblies 10 which may be disposed in vertically stacked relationship. It is considered that only one of the assemblies 10 need be illustrated to convey a full and complete understanding of the construction and functioning of the structure embodying such principles.

Assembly 10 includes a polygonal, planar support 18 suitably secured in generally horizontal disposition in machine 12. A pair of circular, vertically spaced plate members 20 and 22 are rotatably mounted on support 18 and are maintained in vertically spaced relationship by a cylindrical inner wall 24 extending between the inner annular margins of upper plate member 20 and lower plate member 22.

Lower member 22 includes an integral, circumferentially extending, downturned flange 26 having a series of equally spaced apertures 28 therein. The apertures 28 are of uniform size and are disposed so that the center lines of respective apertures 28 lie on radii spaced evenly at 5° 37½' intervals around member 22.

Member 22 is carried for rotation by support 18 by the means of a plurality of upturned, U-shaped brackets 30 secured to the upper surface of support 18 and mounting therein rollers 32 in disposition for engaging the bottom surface of member 22, as best seen in FIGS. 4 and 5.

Members 20 and 22 comprise product-carrier means rotatable past opening 16. The members 20 and 22 carry therebetween product compartment defining means in the form of dividing structures broadly designated 34. Each

structure 34 includes a vertically disposed wall 36 having a first leg 38 commencing proximal the outer peripheral margin of members 20 and 22 and extending generally along a radius thereof until merging into a second leg 40 which is integral with leg 38 and is bent at a slight angle therefrom as shown in FIG. 1. The innermost margin of leg 40 terminates in an integral tab 42 which is received in a vertically extending slot 44 in wall 24. Another

vertically disposed wall section 46 integral with tab 42 extends outwardly therefrom at an acute angle from leg 40 and merges into a leg 48 which extends into contact with wall 36 as shown in FIG. 1.

A tab 50 integral with the lowermost margin of wall section 46 is received in a slot 52 in member 22 to aid in the support of dividing structure 34 and cooperates with a cylindrical portion 54 at the outer vertically extending margin of leg 38 receiving therein pin means 56 to secure structure 34 in place. It may be seen from FIG. 5 that pin means 56 extends through an aperture (not shown) in member 20, passes through portion 54 and is received in an aperture (not shown) in member 22.

As shown in the drawings, structures 34 are disposed at regular intervals around the periphery of assembly 10, each structure 34 being circumferentially spaced from an adjacent structure 34. A vertically disposed, substantially rectangular wall member 58 extending generally parallel to leg 38 of wall 36 has an outer, cylindrical portion 60 receiving therein pin means 62 identical to pin 56. Pin means 62 cooperates with an integral depending flange member 64 on member 58 to hold the latter in vertical disposition and extending generally on a radius of the circular members 20 and 22. Thus, wall section 46 of a dividing structure 34 with the leg 40 of the next adjacent structure 34 and member 58 with leg 38 of the adjacent structure 34 cooperate to define therebetween a generally rectangular product compartment 66.

Compartment 66 is additionally divided into a forward chamber 68 and a rear chamber 70 by a door 72 pivoted to members 20 and 22. As best seen in FIG. 2, door 72 includes a plate 74 pivoted by means of an integral tab 76 on the lower margin of plate 74 to member 22 by means of a bushing 78 disposed in an aperture 80 in member 22.

A second integral tab 82 on the upper margin of plate 74 is received in a generally cylindrical retaining element 84 having a bore 86 therein receiving tab 82. Element 84 may be secured to the upper plate member 20 by screw means 88. A coil spring 90 around element 84 has opposed ends thereof embracing member 20 and plate 74 respectively, to bias door 72 in the direction of the arrow 92 in FIG. 4 and into the position therein illustrated extending generally parallel with wall member 58. An integral depending tab 94 on the lowermost margin of plate 74 extends through an arcuate slot 96 in member 22. Slot 96 extends from a point adjacent member 58 to a point underlying door 72 when the latter is in its normal position across compartment 66 dividing the latter into chambers 68 and 70 of approximately equal size, as shown in FIG. 1.

An elongated, U-shaped barrier 98 is rigidly secured to support 18 and has a bight section 100 extending in vertically spaced relationship from the upper surface of support 18 as best seen in FIG. 5. It will be seen from FIGS. 1 and 4 that barrier 98 is disposed to be engaged by the depending tab 94 of plate 74 for holding the door 72 in its chamber dividing position when compartment 66 is first disposed in substantial registry with opening 16 of the vending machine as shown in FIG. 1. However, when the product carrier is rotated an additional amount in a clockwise direction to the position thereof shown in FIG. 4 with compartment 66 still in substantial alignment with opening 16, the barrier 98 is no longer disposed in a blocking relationship to tab 94 and door 72 is thereby permitted to shift under the bias of spring 90 toward its open position.

A third product-containing chamber 102 is defined between leg 38 of wall 36, leg 48 of dividing structure 34, and wall member 58. The disposition of member 58 and structure 34 is such that chamber 102 is roughly of equal size to chambers 68 and 70.

Means for rotating the product carrier is broadly designated 104, forms no part of the invention per se, and has not been illustrated in detail. It is sufficient to point out

that advancing means 104 includes a member 106 capable of reciprocating movement and includes a pusher element 108 suited to extend into the apertures 28 in flange 26 for advancing the carrier.

Means for limiting the amount of rotation of the product carrier for each occurrence of operation of advancing means 104, irrespective of the number of reciprocations of member 106 for the particular occurrence, comprise clips 110 also not forming a part of the instant invention per se. Clips 110 are received in certain of the apertures 28 and each clip includes a blocking portion 112 disposed to block or close one-half of the particular aperture 28 in which it is disposed. An inwardly extending shoulder portion 114 of each clip 110 cooperates with an inwardly extending leg 116 integral with portion 114 to define a ledge against which pusher element 108 may engage for advancing the product carrier. It is to be pointed out that shoulder 114 is disposed at substantially the center line of the corresponding aperture 28 for a purpose to be hereinafter described.

When a customer, upon deposit of proper coinage in the vending machine, manually opens the closure (not shown) for opening 16 to thereby gain access to the product in the compartment aligned with opening 16, he places the product carrier in position to be advanced by the advancing means 104. The structure for accomplishing this operation includes a pusher rod 118 operably coupled with the closure and which, in turn, operates an indexing member 120. Member 120 has a generally curved finger 122 which is disposed to enter a proximal aperture 28 upon opening of the closure whereby a curved cam edge 124 of finger 122 engages the margin of flange 26 defining the proximal aperture 28 to thereby advance the product carrier through a predetermined arc.

The blocking portions 112 of the respective clips 110 prevent the element 108 from entering the apertures 28 in which the clips 110 are disposed. Thus, as the product carrier is rotated through an arc to bring an aperture 28 into position to be engaged by element 108 for advancing the carrier on the next stroke of member 106, if that aperture 28 contains a clip the element 108 cannot enter into driving relationship in aperture 28. Therefore, so long as the carrier remains in that position of alignment of that clip receiving aperture 28 with respect to element 108, the latter is ineffective for driving the product carrier irrespective of whether member 106 reciprocates or not.

However, the entry of indexing member 120 into an aperture 28 advances the product carrier through a sufficient arc to permit engagement of element 108 with the shoulder portion 114 of the clip 110 on the next reciprocation of member 106. This, then, permits element 108 to advance the product carrier until the next clip 110 is encountered. It will be noted that the indexing member 120 is so disposed in relationship to element 108 that finger 122 is in position to enter the aperture 28 next adjacent the clip 110 which has just previously been encountered by element 108.

It should be pointed out at this juncture that the act of opening the closure for opening 16 by the customer only operates to place the corresponding flange 26 in position for advancing the product carrier, and assuming a plurality of vertically stacked carriers, does not have any effect on the other product carriers of the vending machine.

The member 106 is caused to be reciprocated a predetermined number of times by mechanism (not shown) which is automatically actuated by the returning of the closure for opening 16 to its normal closed position.

In the preferred embodiment of this invention, the clips 110 are spaced around flange 26 in a series of successive patterns with respect to the apertures 28. The repeated pattern comprises the disposition, in succession, of two apertures without clips, an aperture with a clip, two apertures without clips, an aperture with a clip, an aperture without a clip, and an aperture with a clip.

In operation, the chambers of the product carriers are each filled with a product 126 shown by dotted lines in the drawings. Chambers 68 are illustrated containing product 126a, while chambers 70 and 102 are shown containing products 126b and 126c, respectively. The products 126a in chambers 68 serve to hold door 72 in its dividing position between chambers 68 and 70.

Upon deposit of proper coinage into vending machine 12, release mechanism (not shown) is actuated to permit the customer to open the closure for opening 16. This operation causes the advancement of pusher rod 118 to in turn move indexing member 120 into registry with the proximal aperture 28 of flange 26 for advancing the product carrier a sufficient amount so that element 108 will again be effective to drive the product carrier after the closure for opening 16 has been returned to its normal closed position.

Referring now to FIG. 1 wherein is shown the vending machine with chamber 68 aligned with opening 16, it may be seen that the product 126a may be moved by the customer. Indexing member 120 has caused advancement of the product carrier to a position where, when the closure for opening 16 is returned to its closed position, the element 108 engages portion 114 of clip 110 for advancing the product carrier as member 106 reciprocates.

Each succeeding stroke of element 108 causes further rotation of the product carrier until the next clip 110 is brought into position where blocking portion 112 thereof prevents element 108 from entering into driving engagement with the corresponding aperture 28. This terminates the rotation of the product carrier even though member 106 may continue to reciprocate. Element 108 can only resume driving relationship with the product carrier after the latter has been advanced the amount caused by entry of the finger 122 into an aperture 28 as has been heretofore described.

Even though the product 126a is removed from chamber 68, the door 72 is not permitted to open under the bias of spring 90. Instead, barrier 98 cooperates with tab 94, when component 66 is in the position shown in FIG. 1, to prevent customer access to chamber 70 through chamber 68.

The spacing of only one aperture between the clip 110 adjacent element 108 and the next succeeding clip 110 as the product carrier is rotated in a counterclockwise direction as viewed in FIG. 1, permits the product carrier to be rotated through only a relatively short arc before element 108 is stopped from driving the product carrier by such succeeding clip 110. Such rotation is sufficient, however, to move tab 94 on door 72 past barrier 98 so that door 72 is swung to the open position thereof as shown in FIG. 4. The removal by the customer of product 126a before the closure for opening 16 was closed now permits door 72 to open automatically as the product carrier is rotated through a sufficient arc for tab 94 to clear barrier 98.

Because the rotation effected after the vending of product 126a from chamber 68 is relatively small, machine 12 is left in position for vending product 126b from chamber 70 with compartment 66 still in substantial alignment with opening 16 as shown in FIG. 4. The operation of the machine by the customer to permit access of product 126b through chamber 68 causes slight rotation of the product carrier whereby element 108 may again drive the product carrier when the closure is again returned to its closed position.

It may be seen from FIGS. 4 and 6, however, that there are two apertures between these next succeeding clips 110 and this allows the product carrier to be rotated through a relatively greater arc until the succeeding clip 110 is reached whereby element 108 is halted from driving the carrier. Such greater arc is sufficient to bring chamber 102 into alignment with opening 16. Thus product 126c is in position for vending and is accessible to the

customer upon deposit of sufficient money for unlocking the closure for opening 16.

Following the vending of product 126c from chamber 102, the product carrier is again rotated in the manner heretofore set forth, until element 108 engages the next clip 110 encountered as the product carrier rotates. This clip 110 is also spaced from the previous clip 110 by two open apertures so that the carrier is again rotated through a relatively large arc. Such arc is sufficient to bring the next adjacent chamber 68 into substantial registry with opening 16 so that its corresponding product 126a may be vended therefrom.

From the foregoing, it will be apparent that all of the chambers 68, 70 and 102 of the assembly 10 are each successively moved into vending position with respect to opening 16 in the manner set forth.

The spacing of the clips cooperates with the novel structure herein described to permit the movement of the product carrier through two equal arcs for the vending of products from chambers 102 and 68 and then through a smaller arc to effect unlocking of door 72 to permit vending of the product from chamber 70 without removing chamber 68 from substantial registry with opening 16. The smaller arc of advancement of the product carrier permits customer access to chamber 70 through chamber 68 without removing the latter from substantial registry with opening 16. To facilitate the maintenance of chamber 68 in substantial registry with opening 16 despite advancement of the product carrier, it is to be noted that the effective width of access opening for chamber 68 is substantially less than product delivery opening 16. That portion of the outer periphery of member 22 which is along the front of chamber 68, is substantially greater than that which is along the front of chamber 102 to provide clearance for door 72 when open as shown in FIG. 4.

It is readily apparent that the novel structure herein set forth permits a substantial increase in the product vending capacity of vending machines of the type herein referred to.

Having thus described the invention, what is claimed as new and desired to be secured by Letters Patent is:

1. In a vending machine having a product delivery opening therein:
  - a support unit adapted to be mounted within the machine adjacent said delivery opening;
  - a rotatable product carrier mounted on said support unit and having structure thereon defining a series of product-receiving compartments independently registerable with the delivery opening upon rotation of the carrier;
  - shiftable means on said carrier dividing each of the compartments into forward and rear chambers each adapted to receive one of said products; and
  - means on the support unit and operably associated with said shiftable means for maintaining the latter in disposition permitting customer access to only the forward chamber of a respective compartment when the latter is located in a first position in substantial alignment with said product delivery opening and permitting shifting of said shiftable means into a location providing customer access to the rear chamber of the respective compartment when the latter is in a second position in substantial alignment with the product delivery opening whereby the capacity of the vending machine is increased by enlarging the number of chambers from which products are vended.

2. A machine as set forth in claim 1, wherein said shiftable means includes a door pivotally mounted on the carrier.

3. A machine as set forth in claim 2, wherein the carrier includes a generally planar plate member having a slot therein, said door having a tab disposed to extend through the slot and shiftable therein when the door is

pivoted, and wherein is included an elongated barrier rigidly secured to the support unit in disposition to be engaged by the tab to prevent pivoting of the door when the compartment is located in said first position.

4. A machine as set forth in claim 1, wherein is included spring means operably coupled with said shiftable means for biasing the latter toward said location.

5. A machine as set forth in claim 1, wherein each of the structures defining said compartments is disposed in horizontally spaced relationship from an adjacent compartment defining structure to present therebetween a third product receiving chamber.

6. A machine as set forth in claim 5, wherein the carrier is provided with a pair of opposed, upright side walls disposed to define a generally rectangularly shaped compartment, said shiftable means being disposed to divide the compartment into two chambers of substantially equal size.

7. A machine as set forth in claim 6, wherein the shiftable means includes a door pivoted on the carrier and extending across said compartment and substantially normal to said side walls when the shiftable means is in said chamber-defining disposition thereof, there being a depending tab on the door, and wherein the carrier includes a plate member underlying said structures, there being a slot in the plate member receiving the tab and extending from a point underlying the door when the latter is in the chamber-defining disposition thereof to a point proximal one of said side walls, and an elongated barrier rigid to the support and disposed to be engaged by said tab for holding the door in said chamber-defining disposition when the compartment is in said first position, the barrier being disposed to be cleared by the tab when the compartment is in said second position whereby the tab may move in the slot to permit pivoting of the door to a position substantially parallel to said one wall.

8. In a vending machine having a housing provided with a delivery opening therein, a support unit mounted within the housing adjacent the delivery opening, a rotatable product carrier mounted on said support unit in alignment with the delivery opening, said carrier having a peripheral flange thereon provided with a series of apertures therein, and article carrier advancement mechanism within the housing and including a shiftable element disposed to engage the flange within said apertures therein as the element is shifted to thereby effect rotation of the carrier while the element is coupled to said carrier flange, the combination with said support unit and the carrier of:

divider means on the carrier located in nominally radially extending relationship with respect to the axis of rotation of the carrier and defining a series of outwardly facing product-receiving compartments independently registrable with the delivery opening; shiftable means on the carrier dividing each of the compartments between said divider means into forward and rear chambers, each adapted to receive one of said products;

a barrier on the support unit in underlying relationship to said carrier and operably associated with said shiftable means for maintaining the latter in disposition permitting customer access to only the forward chamber of a respective compartment when the latter is located in a first position in substantial alignment with said product delivery opening and permitting shifting of said shiftable means into a location providing customer access to the rear chamber of the respective compartment when the latter is in a second position in substantial alignment with the product delivery opening; and

means on the flange of said carrier within said apertures thereof for effecting uncoupling of said element from the carrier after rotation of the latter through an arc to shift the carrier from said first position to the second position of the same during one period of actuation of said mechanism and for effecting uncoupling of the element from said carrier after rotation of the latter from the second position to the first position thereof of another compartment during another period of actuation of the mechanism.

9. A machine as set forth in claim 8, wherein the flange of said carrier is provided with eight apertures between the divider means defining one compartment and a corresponding divider means of the next adjacent compartment.

10. A machine as set forth in claim 9, wherein said flange is provided with a series of equally spaced apertures throughout the entire periphery thereof.

11. A machine as set forth in claim 10, wherein said uncoupling means includes a plurality of clips, each clip being secured in one of said apertures, said clips being spaced around the flange in a series of successive patterns with respect to the apertures, the pattern comprising in succession: two apertures without clips, an aperture with a clip, two apertures without clips, an aperture with a clip, an aperture without a clip, and an aperture with a clip.
